(22) Filed: **Dec. 29, 2016**

(57) **CLAIM**

The ornamental design for a cleavage-enhancing garment insert, as shown and described.

DESCRIPTION

(63) Continuation of application No. 29/459,093, filed on Jun. 26, 2013, now Pat. No. Des. 775,452.

FIG. 1 is a view of the cleavage-enhancing garment insert inside of a bra;

(51) **LOC (10) Cl.** **02-01**

FIG. 2 is a rear view of the cleavage-enhancing garment insert;

(52) **U.S. Cl.**

FIG. 3 is a front view of the cleavage-enhancing garment insert;

(58) **USPC** **D2/706**

FIG. 4 is a left view of the cleavage-enhancing garment insert;

Field of Classification Search

FIG. 5 is a right view of the cleavage-enhancing garment insert;

USPC D2/700, 701, 703, 705, 706, 707, 708,
D2/709, 710, 736, 737, 855; D5/6, 11
CPC . A41C 3/065; A41C 3/10; A61F 2013/15016;
A61F 13/14

FIG. 6 is a top view of the cleavage-enhancing garment insert; and,

See application file for complete search history.

FIG. 7 is a bottom view of the cleavage-enhancing garment insert.
